UNITED STATES PATENT OFFICE.

CLARENCE C. STIRLING, OF HARTFORD, CONNECTICUT.

ELECTRIC SWITCH.

1,383,349.

Specification of Letters Patent.

Patented July 5, 1921.

Application filed September 26, 1918. Serial No. 255,738.

To all whom it may concern:

Be it known that I, CLARENCE C. STIRLING, a citizen of the United States, residing at Hartford, in the county of Hartford and 5 State of Connecticut, have invented certain new and useful Improvements in Electric Switches, of which the following is a specification.

This invention relates to electric switches, 10 the object of the invention being to provide an article of this character which is quite simple in construction, comprises a comparatively small number of parts and is positive and certain in action. The device 15 involves other features of novelty and advantage, which with the foregoing will be stated at length in the following description, wherein I will set forth in detail that form of embodiment of the invention which I 20 have selected for illustration in the drawings accompanying and forming part of the present specification. I do not necessarily restrict myself to this exact disclosure; I 25 may depart therefrom in several respects within the scope of the invention defined by the claims following said description.

Referring to said drawings:—

Figure 1 is a transverse section of a switch 30 involving the invention.

Fig. 2 is a horizontal section on the line 2—3 of Fig. 1, looking in the direction of the arrows, and showing the parts in the 35 positions in which they appear in said Fig. 1.

Fig. 3 is a practically similar view, the 40 full lines showing the switching member in the closed position, the dotted lines in the open position, and the spring on the left in the condition it appears practically prior to the commencement of the snap movement.

Fig. 4 is a horizontal section on the line 45 4—4 of Fig. 1, looking in the direction of the arrows.

Fig. 5 is a fragmentary detail on a larger 50 scale and in elevation, of certain of the parts hereinafter more particularly described.

Like characters refer to like parts throughout the several views.

The different parts of the switch may be 55 sustained in any desirable manner. For this purpose I have shown a supporting body as

2 practically in the form of a disk of some insulating material such as is ordinarily used in this art. There is associated with said body or base 2 a shell or case as 3, 55 usually of metal and practically cylindrical, the marginal portion of said shell or case being set in a rabbet or channel as 4 in said body or base. Within the metal shell or case 3 is a lining as 5 of some suitable insulating material, the lining being of a shape to conform practically to that of the shell or case.

The body or base 2 as shown practically supports centrally thereof the spindle 6 65 which extends through a central opening in the body or base and which is held in assembled relation therewith by the key 7 fitting a peripheral channel in the hub or sleeve 8 fastened to the lower end of the 70 spindle. The action of the switch is controlled by a detent as 9 fastened centrally to the upper or inner surface of the body or base 2. Centrally through this detent extends the spindle 6, it being clear, of course, 75 that the spindle turns with respect to the detent which, as I have practically observed, is stationary. As a matter of fact while the spindle rotates in either direction, it does so with an intermittent or step-by-step 80 movement. This, however, is not essential.

The body or base 2 sustains complemental or diametrically opposite clips as 10 constituting convenient contacts and which are held to said body or base by screws as 11. 85 With these screws or with the contacts or clips 10 are connected the wires. It will be evident that when the contacts or clips 10 are bridged, the switch will be closed. The switching member or contactor may be of 90 any desirable kind. That shown is denoted in a general way by 12 and consists of a practically flat plate or strip centrally through which just above the detent 9 the spindle 6 freely extends. Although the 95 spindle is the prime means for effecting the necessary action of the switching member or contact 12, the action is not, however, a direct one. The spindle may be operated in any desirable manner as by the actuator or 100 knob 13 rigid therewith at the upper end thereof, this upper end extending through

registering openings in the shell or case 3 and lining 5. Therefore, through the manipulation of the knob 13, the spindle 6 can be turned to effect the necessary action of 5 the switching member or contactor 12.

The switching member in addition to the rotary or oscillatory movements to which I have already referred, has an endwise movement for a reason that will hereinafter appear. It should be noted that the opening 14 through which the spindle 6 extends is in 10 the form of a longitudinal slot in said switching member. In view of this circumstance the latter may when occasion requires be moved endwise. Surmounting the 15 switching member is a block or washer 15, the two opposite faces of which are flattened as at 16 to coöperate with opposite pins as 17 rising from the central portion of the 20 switching member or contactor 12. I might explain that through this block or washer 16 the spindle 6 extends, the spindle being rotative with respect to the block or washer which functions in effect as a latching member. The detent or disk 9 has peripheral 25 notches 18 arranged practically 90 degrees apart and coöperative with a stop or projection as 19 rigid with the endwise movable and turnable switching member 12, the stop 30 or projection being shown in for instance Figs. 1 and 5 as occupying one of the notches 18 to thus maintain positively the switching member in a desired position. The spindle as shown is furnished with a hook-like 35 projection 20 to which is connected one end of the spring 21, the other end of said spring being shown connected to a screw as 22 near one outer end of the switching member on the upper side thereof. This spring in 40 the present case constitutes a convenient means when conditioned, for imparting the necessary snap movement to the switching member, to move the same from the on to the off relation or vice versa. Practically co- 45 axial with this coiled spring 21 is a second spring as 23, the inner end of the second spring being connected with the washer or block 15 already described, and the outer 50 end thereof being connected with a screw 24 adjacent the outer upper end of the switching member, and constituting a convenient means for imparting a retractive movement to the switching member to facilitate the entry of the projection or catch 20 55 into the appropriate one of the several notches 17.

In Figs. 1 and 2 for illustration the switch is shown as on, the switching member or contactor 12 at this time bridging the diametrically opposite contacts 10; that is the ends of the switching member are disposed 60 between the branches of said contacts or clips. At this particular time the projection or catch 19 is then in a peripheral notch 18. It will be assumed that it is desired to

open the circuit for illustration by turning the switching member or contactor 12 in the direction of the arrow in Fig. 2. In this event the following procedure will be adopted: The knob 13 will be grasped and 70 turned, thus correspondingly turning the spindle 6 and carrying the projection 20 therewith so as to stretch the spring 21. As the spindle continues to turn in the direction indicated, the said projection will strike 75 the upper of the two pins 17 and thus bodily move the switching member 12 toward the right in Fig. 1 and carry thereby the projection or catch 19 out of the notch 18 it is occupying, the motion continuing in this 80 manner until said projection or catch 19 is fully out of its slot when the switching member will be released and may be turned in the direction indicated by the arrow through the stretched spring 21. On the 85 endwise movement of the switching member 12 toward the right in said Fig. 2, the spring 23 is stretched, so that when the switching member has made a quarter of a turn 90 through the action of the spring 21, the 95 spring 23 will impart an opposite endwise movement to the switching member so as to move the catch, stop or projection 19 into the notch 18 next around from the notch it had last occupied and thus positively arrest 100 the further motion of the switching member through impetus for instance, because at this particular time the spring 21 is practically inert. The dotted lines in said Fig. 3 show the switching member 12 in its open circuited position, and it can be shifted to circuit closing position in either direction, although said dotted lines in the particular view show the open relation. The switching member 12 is not actually freed, nor 105 will it be until the projection, catch or stop 110 19 is wholly moved out of the notch 18 which it may be for the time occupying. In said Fig. 3, however, the spring 21 is practically under maximum stretch, and the stop or projection 19 is almost out of its notch or slot.

What I claim is:

An electric switch comprising a detent having notches in its periphery, a turnable 115 spindle coaxial with and extending through the detent, a switching member having a longitudinal slot through which the spindle turns, the switching member being capable of turning movement relatively to the 120 spindle and also for movement in an endwise direction, and being provided with a catch to normally enter a notch in the detent, a block on the switching member and through which the spindle extends, the block 125 having opposite flattened faces, pins on the switching member, normally engaging opposite faces of the block, a coiled spring connected respectively with the block and with the switching member in an endwise 130

direction to carry the catch out of the notch it occupies, at the same time to stretch said spring and also to move the pins free of the flat faces of the block, the stretched spring when the catch is out of the notch imparting a snap movement to the switching member, and a second coiled spring connected with the block and also with the switching member, to move the catch into a

second notch after the switching member 10 has turned a predetermined distance.

In testimony whereof I affix my signature in the presence of two witnesses.

CLARENCE C. STIRLING.
